1

Latin name: *Malus domestica* Borkh.
Variety denomination: 'Foxtrot'.

BACKGROUND OF THE VARIETY

'Foxtrot' is a new and distinct variety of 'Gala'-type apple tree *Malus domestica* Borkh. The new variety is believed to be a whole-tree mutation of 'Tenroy Gala' (U.S. Plant Pat. No. 4,121), and is characterized by its large, intense red early maturing fruit. 'Foxtrot' was first observed in a commercial orchard planted with 'Tenroy Gala' trees near Quincy, Wash. in 2004. After three seasons of observation, the variety was asexually reproduced by grafting to determine whether the desirable characteristics of fruit size, color and early maturity would carry through to subsequent generations. Wood from the second generation trees was grafted onto 'M26' rootstock and planted in a larger commercial planting in 2009 for further observation. 'Foxtrot' has been observed to remain true to type over successive asexually propagated generations.

BRIEF DESCRIPTION OF THE VARIETY

'Foxtrot' is a 'Gala'-type apple variety. It was first selected for its intense red fruit. It is distinguished from 'Tenroy Gala' and other Gala-type varieties by its large, intense red early-maturing fruit and exceptional flavor.

BRIEF DESCRIPTION OF THE PHOTOGRAPHS

FIG. 1 shows the blossoms of the 'Foxtrot' apple tree;
FIG. 2 shows a 'Foxtrot' apple tree in bloom;
FIG. 3 shows the leaves of the 'Foxtrot' apple tree;
FIG. 4 shows fruit of the 'Foxtrot' apple tree;
FIGS. 5 and 6 show sectioned fruit of the 'Foxtrot' apple tree;
FIG. 7 shows the fruit and leaves of the 'Foxtrot' apple tree;
FIG. 8 shows a 'Foxtrot' apple tree;
FIG. 9 shows a 'Tenroy Gala' apple (left) and a 'Foxtrot' apple (right); and

FIG. 10 shows trees of the 'Tenroy Gala' variety (left) and the 'Foxtrot' variety (right).

DETAILED BOTANICAL DESCRIPTION OF THE VARIETY

The following-detailed botanical description is based primarily on observations made during the 2012 growing season near Connell, Wash. The observed trees were planted in 2009 and grown on 'M26' rootstock (not patented) in trellised high-density plantings. All colors are described according to The Royal Horticultural Society Colour Chart. It should be understood that the characteristics described will vary somewhat depending upon cultural practices and climatic conditions, and will vary with location and season. Quantified measurements are expressed as an average of measurements taken from a number of individual plants of the new variety. The measurements of any individual plant or any group of plants of the new variety may vary from the stated average.

Tree:

Vigor.—Moderate (similar to 'Tenroy Gala').

Type.—Spur-type.

Habit.—Upright.

Height.—3.3 m.

Trunk diameter (at 30 cm above the graft).—5 cm.

Bark texture.—Smooth with prominent lenticels.

Bark coloration.—Grey-brown N200C, N200D, with areas of Grey-brown 199B.

Branch (fruiting branches located at around 1 m above the graft union):

Length.—30 to 60 cm.

Diameter.—2 to 3 cm.

Crotch angle.—45 degrees to 90 degrees.

Bark color.—Greyed-brown N200C, N200D.

35 One year old shoot:

Length.—30 cm.

Color.—Grey-brown 197B; Grey-brown 200D.

Pubescence.—Moderate (same as 'Tenroy Gala').

Thickness.—5 to 6 mm.

Internode length.—3 to 5 cm.

Number of lenticels.—4 to 6 per cm².

Flower buds:	Fruit:
Quantity per spur.—5.	Quantity per cluster.—One.
Shape.—Pointed.	Diameter.—8 cm.
Length.—5 mm.	Weight.—225 g.
Diameter.—5 mm.	5 Ratio of height to width.—Equal.
Color (at time of bud burst, prior to opening).—Red-purple N57.	General shape in profile.—Conic.
Flowers:	Position of maximum diameter.—Equator.
Diameter of fully open flower.—6 cm.	Ribbing.—Absent.
Relative position of petal margins.—Touching.	10 Crownning at calyx end.—Present.
Number per cluster.—5.	Size of eye.—1 cm.
Date of first bloom (2013).—April 18.	Aperture of eye.—Closed.
Date of full bloom (2013).—April 23.	Length of sepal.—6 mm.
Pollinator.—Required.	Bloom of skin.—Absent or weak.
Petals:	Greasiness of skin.—Absent or weak.
Number per flower.—5 to 6.	Background color of skin.—Yellow 7D.
Shape.—Orbicular.	Amount of over color.—90 to 100%.
Length.—3 cm.	Over color of skin.—Red 45A, 44B.
Width.—1.5 cm.	Intensity of over color.—Strong to very strong.
Apex.—Obtuse.	20 Pattern of over color.—Solid flush with weakly defined stripes.
Base.—Aequilateral.	Amount of russet around stalk cavity.—None.
Margin.—Entire, cupped.	Amount of russet on cheeks.—None.
Color of upper surface.—White to pale pink, with tinges of Red-purple N66C.	Area of russet around eye basin.—None.
Color of lower surface.—White to pale pink, with tinges of Red-purple N66C.	25 Length of stalk.—3 cm.
Pistils:	Thickness of stalk.—3 mm.
Stigma.—Yellow 11C.	Depth of stalk cavity.—2 cm.
Style.—Yellow-green 145D.	Width of stalk cavity.—3.5 cm.
Ovary.—Yellow-green 145D.	Depth of eye basin.—1.3 cm.
Stamen:	Width of eye basin.—3 cm.
Quantity.—18 to 20.	30 Firmness of flesh.—21 lbs. (at 5 days before harvest).
Anther.—Yellow 11D.	Flesh texture.—Crisp, fine.
Filament.—White NN155C.	Aroma.—Fragrant, floral.
Pedicel:	35 Juiciness.—Juicy, similar to 'Tenroy Gala'.
Color.—Yellow-green 144D.	Brix.—12 (at 5 days before harvest).
Sepals:	Flesh color.—Green-white 157D.
Quantity.—5.	Stem color.—Grey-brown N199D.
Shape.—Pointed.	Seeds:
Margin.—Entire.	40 Quantity per fruit.—4 to 7.
Color.—Yellow-green 145A, pubescent.	Shape.—Teardrop shape.
Leaves:	Coloration.—Grey-brown N199B, N199C.
Shape.—Ovate.	Harvest:
Length.—11 cm.	Time for harvest.—Late August, about 5 days prior to 'Tenroy Gala'.
Width.—6 cm.	45 Number of picks.—One.
Blade margin.—Serrate.	Harvest yield.—35 tons per acre (based on high-density planting of 1100 trees per acre).
Apex.—Acuminate.	Disease resistance/susceptibility: None noted.
Base shape.—Aequilateral, oblique.	Market use: Fresh.
Color of upper surface.—Yellow-green 144A, Green N137A.	
Color of lower surface.—Yellow-green 147B, 147C.	
Attitude in relation to shoot.—Upward.	
Petiole:	
Length.—3 to 3.5 cm.	
Diameter.—2 to 3 mm.	
Color.—Yellow-green 144D with some anthocyanin coloration.	

The invention claimed is:

1. I claim a new and distinct apple tree substantially as described and illustrated herein.
